UNITED STATES PATENT OFFICE.

ALFRED GRIEB, OF ELIZABETH, NEW JERSEY, ASSIGNOR TO THE SINGER MANUFACTURING COMPANY, A CORPORATION OF NEW JERSEY.

SEWING-MACHINE.

1,206,433.

Specification of Letters Patent. Patented Nov. 28, 1916.

Application filed February 26, 1915. Serial No. 10,678.

To all whom it may concern:

Be it known that I, ALFRED GRIEB, a citizen of the United States, residing at Elizabeth, in the county of Union and State of New Jersey, have invented certain new and useful Improvements in Sewing-Machines, of which the following is a specification, reference being had therein to the accompanying drawings.

- 10 This invention relates to sewing machines adapted for sewing sweat bands into hats; and it has for its object to provide an efficient, durable and compactly arranged construction in which the hat-supporting elements and the feeding and presser-wheels are relatively-movable for the easy insertion and withdrawal of the hat, the primary hat-supporting member being a circular disk mounted for universal movement, and 20 carried by a spring-pressed treadle-operated presser-arm which carries the presser-wheel and certain cord- and hat-guiding elements.

The improvements are employed in conjunction with stitch-forming mechanism of a known construction, in which the horizontal-reciprocating needle-bar co-operates with a reciprocating and laterally movable looper operated by a cam-wheel on the 30 driving shaft, and the feeding mechanism comprises a horizontally-disposed wheel formed with a serrated peripheral face.

Rising from the bed-plate of the machine is an angular arm, its upper portion being 35 bent downwardly and at its end formed with a bearing boss to receive a freely-movable presser wheel, the latter being fitted upon an upright stud or post which is threaded at its upper end to receive a fastening screw for a rectangular needle-block. The block is formed with a needle-way for the needle and with a loop-finger which co-operates with the looper. Mounted upon the presser-arm, and overhanging the 45 presser wheel is an adjustable bracket which supports a rigid guide-finger for the hat fold and also a pivotally mounted cord-guide, the said guides being disposed at opposite sides of the needle path. The primary hat-supporting member is a circular disk having a ball-and-socket connection with a spring-pressed arm which serves to hold the fold of the hat brim against the lower faces of the overlying fold-guide and

cord-guide. The secondary hat-supporting member is a segmental plate pivotally supported upon the presser-arm, so that it may yield laterally to conform with various sizes and shapes of hats.

The upper section of the presser-arm is rigidly connected with a lower section which is pivotally supported below the work-plate of the machine and which is formed with a rearwardly extending spring-pressed treadle-operated arm so that the faces of the presser- and feed-wheels, normally brought into yielding contact, may be separated when the treadle is depressed. And the ball connection between the hat-supporting disk and the frame-arm permits the disk to be tilted away from the presser-wheel when the presser-arm is retracted, to afford free spaces between the presser-wheel, the supporting disk, and the feed-wheel.

In the drawings, Figure 1 is a perspective view, partly in section, of the improvements, the frame of the machine being shown in dotted lines. Fig. 2 is a perspective view, of certain parts of the improvements removed from the machine, a hat being shown supported in sewing position. Fig. 3 is a perspective view partly in section, of the presser- and feed-wheels, the needle-block, loop-finger, cord- and - fold guides, the needle and the looper, showing a stitch in the process of formation. Fig. 4 is a perspective view from the under side of the cord-and-fold guides and their supporting bracket. Fig. 5 is an elevation, partly in section, of the presser- and feed-wheels and hat supporting disk.

The improvements are shown applied to a sewing machine formed with a base A, bed-plate B and upright standard C. Extending transversely through the standard C is the driving shaft 1 provided with the balance-wheels b—b and the grooved belt-pulley 2. Mounted for horizontal reciprocation within suitable bearing members of the standard C is the needle-bar 3 provided with the needle-clamp 4 in which is secured the needle 5. Co-operating with the needle is a looper 6 secured within the sleeve 7 of a pivotally mounted arm which receives reciprocating and lateral movements from the looper actuating cam 9 and other connections with the driving shaft 1. Rising from the bed-plate of the machine is a vertical

shaft 10 which supports upon its upper end the horizontally disposed feed-wheel 11 which receives intermittent feeding movements from suitable driving devices not shown. The structural characteristics of the stitch-forming mechanism thus briefly described form no part of the present invention and further description thereof is unnecessary.

10 The presser-wheel 12 which co-operates with the feed-wheel 11, is mounted for rotation within a bearing boss 13 formed at the end of the depending portion 14^x of the presser-arm 14 which rises from below the bed-plate of the machine. The presser-wheel rotates upon the reduced portion of a stud 15 which is clamped within the bearing boss 13 by means of a clamping screw 16. A needle-block 17 is secured upon the upper 15 end of stud 15 by means of a screw 18, so that the lower face thereof will meet the upper face of the presser-wheel 12 and thus serve to hold the latter in position. The needle block is provided with a lug 17^x having a wall disposed adjacent the path of reciprocation of the needle; and at the opposite side of the needle path the block is provided with an adjustable loop-finger 19 which is the complement of lug 17^x in providing a guard for the needle, and which at its end is formed with an upturned laterally-extending portion 19^x over the beveled face of which the loop is drawn by the looper during the retraction of the needle, 20 so that the pull of the thread, as the looper moves transversely of the needle puncture to position the loop, is upon the finger rather than upon the sweat band, and the latter is not cut by the thread. The loop-finger is 25 so positioned with respect to the looper that the loop passes off the same before it is entered by the needle.

The boss 13 of the presser-arm is formed with a flat seat 20 disposed immediately below the presser-wheel 12 and adapted to receive the base portion 21^x of a bracket 21, a screw 22 passing through an elongated aperture in the bracket serving to permit vertical adjustment of the latter. The angular upper portion of the bracket 21 is formed with a flat horizontally-disposed seat which overhangs the presser-wheel and which is apertured to receive a screw 23 passing through an elongated aperture formed in a bracket extension 24 to which is fixed by means of the screws 25 a curved guide-finger 26 which projects slightly beyond the presser and the feed-wheels. The bracket extension 24 also affords a support for a cord-guide 27 which is pivoted thereto by means of a stud-screw 28 and which is formed with an upwardly extending finger piece 29. The cord-guide is provided with a nose 30 which projects slightly beyond the periphery of the presser-wheel and which is

apertured to receive and guide the cord c, the cord passing also through an aperture formed in the finger piece 29 of the guide. It will be seen that the formation of the bracket 21 and its extension 24 will permit the guide-finger 26 and cord-guide 27 to be bodily adjusted either vertically or horizontally to conform with various thicknesses of material or changes desired in the depth of stitch position of the cord &c.

The primary hat-supporting member is a disk 31 having a beveled face 31^x and formed with a central aperture into which is fitted a substantially spherical head or ball 32 at one end of a stud 32^x clamped by 30 a set-screw 33 within an aperture formed in the end of an arm 34 loosely mounted upon a pin 35 clamped by means of a screw 36 within an aperture formed in the presser-arm. The disk 31 is held on the ball 32 by 35 means of a cap piece 37 which has a central aperture shaped to fit the forward portion of the ball and which is secured to the disk by means of the screws 38. The disk-carrying arm 34 is formed with a depending lug 39 in contact with a thumb-screw 40 within a suitable threaded aperture on the presser-arm. By turning the thumb-screw 40 to the right the disk may be raised against the stress of a spring 41 having one end secured to the arm 34 and the opposite end fitted within an aperture formed in the fixed pin 35, and by turning the thumb-screw in the reverse direction the disk may be lowered by the action of the spring 41.

The secondary hat-supporting member is a segmental guide-plate 42 secured at its lower end to a swinging-bar 43, the apertured end of the bar being clamped by means of screws 44, upon a pin 45 loosely fitted within the apertured lugs 46 of an angular arm 47 which is formed with a rib 47^x which fits within a recess formed in the face of arm 14, a screw passing through an elongated aperture in the arm 47 serving to 105 adjustably secure the same in position. Lateral movement of the guide-plate 42 is limited by means of a stop, the stop comprising a plate 49 secured to the angular arm 46 by means of screw 50 and bent upwardly at 49^x to project above the lower edge of the disk.

As hereinbefore stated, the arm 14 comprises two sections. The lower section of the arm lies entirely beneath the bed-plate 120 and projects rearwardly to a point below the standard C of the machine. The base of the upper section of the arm is, in this instance, circular in form and is reduced at its lower end, as indicated by the numeral 51, in Fig. 1, to fit within an aperture formed in the lower presser-arm section, the two sections being clamped together by a screw 52. The connected presser-arm sections are mounted to rock on trunnions or 125 130

center screws, one of which is indicated by the numeral 53 in Fig. 1. The rearwardly extending portion 54 of the lower presser-arm section is normally pressed downwardly by means of a spring 55 fitted within the standard C, the spring serving to press the presser-wheel toward the serrated peripheral face of the feed-wheel. When it is desired, however, to place a hat in sewing position or to remove a hat from the machine, the presser-arm is moved upwardly against the stress of the spring 55 and the hat-supporting disk 31 and plate 42, and the presser-wheel 12, are bodily moved away from the feed-wheel. To effect this result a lifting lever 56 is provided, the lever being pivoted to the machine frame by means of a stud-screw 57 and having its free end underlying and turned upwardly into contact with the end of the lower presser-arm section. To the opposite end of arm 56 is connected the treadle-rod 58 of a suitable treadle device, by which the presser-arm and its other parts may be retracted by foot pressure to permit the operator to use both hands in inserting work or withdrawing the same from the machine.

It will be seen that the feed-wheel directly engages the brim of the hat near its fold and that the periphery of the disk 31 engages the fold below the path of reciprocation of the needle. Thus the hat is firmly held at the stitching point by the contact of the underlying supporting disk with one face of the material and the opposed toothed feed and presser-wheels with the other face of the material; and vertical adjustment of the supporting disk will determine the depth of stitch.

The form of the cord-guide and its supporting means enables the operator to swing the guide within the periphery of the feed-wheel and thus out of engagement with the hat. Both of the guide-fingers may be adjusted with their supporting bracket both vertically and horizontally to provide for changes in the thickness of the hat material or depth of stitch desired.

It will be understood that various changes may be made in the form and arrangement of the parts without departing from the spirit of the invention. For example, the guide-plate 42 may be straight instead of semi-circular; and the presser-arm 14 may be formed as a unitary member, its sectional construction being convenient in assembling the parts.

Having thus set forth the nature of the invention, what I claim herein is:—

1. In a hat sewing machine, the combination with a frame, a driving shaft, a reciprocating needle and coöperating stitch-forming mechanism connected with said driving shaft, of a feed-wheel, a presser-arm provided with a presser-wheel, and a

vertically disposed supporting disk intermediate the operative faces of the presser and feed-wheels and rotatable about an axis extending transversely of the axis of the presser-wheel to engage a hat at its fold 70 intermediate the brim and crown.

2. In a hat sewing machine, the combination with a reciprocating needle and coöperating stitch-forming members, of yieldingly opposed feed and presser members, a 75 rotatable hat supporting disk having its periphery in a plane intermediate said feed and presser members, and a pivotal support for said disk disposed closely adjacent to said plane.

3. In a hat sewing machine, the combination with a reciprocating needle and coöperating stitch-forming members, of yieldingly opposed feed and presser members, a 85 rotatable hat supporting disk having its periphery in a plane intermediate said feed and presser members, a support for said disk and a universal joint connection between said disk and said support.

4. In a hat sewing machine, the combination with a reciprocating needle and coöperating stitch-forming members, of yieldingly opposed feed and presser members, a 90 rotatable hat supporting disk having its periphery in a plane intermediate said feed and presser members, a support for said disk and a ball and socket connection between said disk and said support.

5. In a hat sewing machine, the combination with a frame, a driving shaft, and 100 stitch-forming mechanism operatively connected with said driving shaft, of opposed feeding and presser-wheels, a hat-supporting disk rotatable about an axis extending transversely of the axis of the presser-wheel, a spring-pressed supporting arm common to the disk and presser-wheel, and means whereby said arm may be retracted against the pressure of its spring.

6. In a hat sewing machine, the combination with a frame, a driving shaft, and 110 stitch-forming and feeding members operatively connected with said driving shaft, of a presser-member, an arm pivotally mounted on the frame and carrying said presser-member, a rotary hat supporting disk mounted upon the presser-arm for lateral movement toward and from the presser-member, and means for moving said arm to simultaneously carry the presser-member and disk toward or from the feeding member.

7. In a hat sewing machine, the combination with a frame, a driving shaft and 115 stitch-forming and feeding members operatively connected therewith, of a presser-member, a presser-arm, a supporting disk and a guide-plate each mounted for lateral movement upon the presser-arm and adapted to engage a hat at its fold intermediate 120 125 130

the brim and crown, and means whereby the presser-arm may be moved toward and from the feeding member.

8. In a hat sewing machine, the combination with a horizontally reciprocating needle and coöperating stitch-forming members, of a feed-wheel, a presser-arm provided with a presser-wheel spring-pressed toward the face of the feed-wheel, a vertically disposed hat-supporting disk intermediate the presser and feeding wheels, and vertically adjustable means for supporting said disk upon a substantially horizontal axis.
- 15 9. In a hat sewing machine, the combination with a frame, a driving shaft and stitch-forming and feeding members operatively connected therewith, of a presser-member, a spring-pressed arm adapted to 20 sustain said presser-member, a hat-supporting disk disposed intermediate the presser and feeding members, a lever fulcrumed upon the presser-arm and having a universal joint connection with the disk, a spring acting 25 upon said lever, and means whereby the lever may be moved upon its fulcrum in opposition to said spring.

10. In a hat sewing machine, the combination with a frame, a driving shaft and 30 stitch-forming and feeding members operatively connected therewith, of a presser-arm provided with a presser-wheel, a bracket adjustably mounted upon said arm and overhanging in the presser-wheel, a 35 guide-finger carried by said bracket and adapted to engage a fold on the hat, and a retractable finger mounted upon said bracket and provided with an apertured projection adapted to receive a cord and to 40 coöperate with said guide-finger.

11. In a hat sewing machine, the combination with stitching mechanism, a feeding wheel and a presser-wheel having opposed toothed faces, of a supporting arm for said 45 presser-wheel, a bracket adjustably carried by said arm, and oppositely disposed guide-fingers adjustably mounted upon said bracket, one of the said fingers being aper-

tured to receive a cord and adapted to be independently moved toward and from operating position.

50 12. In a hat sewing machine, the combination with a horizontally reciprocating needle, a looper adapted to coöperate with said needle, a feed-wheel, a presser-wheel and a presser-arm therefor, of a block on the presser-arm formed with a guideway having parallel walls adjacent the path of the needle, and a thread-engaging finger overhanging the needleway and over which the 55 loop is drawn by the looper prior to the penetration of the loop by the needle.

13. In a hat sewing machine, the combination with a frame, a horizontally disposed feed-wheel, a presser-arm provided 60 with a horizontally disposed presser-wheel, said presser-arm being pivotally supported upon the frame, a spring acting upon the presser-arm to cause the presser-wheel to engage the face of the feed-wheel, a vertically disposed hat-supporting disk carried by the presser-arm, and a treadle operated lever adapted to retract said presser-arm 65 against the action of its spring.

14. In a hat sewing machine, the combination with a frame, a horizontally reciprocating needle and a coöperating looper, of a horizontally disposed feeding wheel, and a horizontally disposed presser-wheel, a presser-arm comprising an upper section 70 and a rocking underlying section to which the upper section is adjustably connected, a spring acting upon the lower presser-arm section to cause the presser-wheel to engage the face of the feed-wheel, and a treadle operated lever mounted in the frame and 75 adapted to act upon the presser-arm in opposition to its spring.

15. In testimony whereof I have signed my name to this specification in the presence 80 of two subscribing witnesses.

ALFRED GRIEB.
